CIGARETTE PACKING MACHINE

Cornelius I. Braren, Jamaica, N. Y., assignor,
by mesne assignments, to Standard-Knapp
Corporation of New York

Application December 11, 1930, Serial No. 501,511

3 Claims. (Cl. 226—14)

This invention relates to cigarette-boxing machines and has for its object to provide a machine which will take cigarette packages from a series of machines which perform the last operation on the cigarette package—usually the application of a transparent wrapper to the packages—and pack a predetermined number of such packages in a carton.

The machine is designed to operate in conjunction with a carton-closing and sealing machine such as disclosed in my copending application Ser. No. 501,513 filed concurrently here-with.

The machine of the present invention receives 15 cigarettes from the delivery belts of a number of the package-finishing machines and places ten of the packages in two rows of five each in a pasteboard carton having upstanding flaps along its four top edges, the carton thus filled being 20 delivered by a discharge belt which may serve to bring the filled but unsealed carton to the machine of my copending application.

Cartons of this type have heretofore been primarily packed by hand for the reason principally 25 that no satisfactory means has heretofore been devised which will invariably and without the constant supervision of the operator, place the desired number of packages of cigarettes in each carton. The difficulty of providing a satisfactory 30 apparatus for this purpose was principally because of the fact that machines from which the packages of cigarettes are received do not furnish continuously a uniform output of cigarette packages. One machine or another may be shut 35 down temporarily for adjustment or repairs. Also, gaps in the delivery lines are occasioned by the inspectors removing defective packages 40 from the conveyors.

In the machine of the present application the 45 difficulty heretofore resulting from this irregularity of the delivery of the packages to the machine is taken care of by controlling the machine through the packages themselves as they are advanced to the carton-filling instrumentalities in such manner that the machine will not operate to feed the packages into the carton unless a full charge of ten packages is present.

The object of my invention is to provide a 50 machine for performing the above-described operations which will be entirely automatic in its operations so that it may be installed between the delivery belts of the cigarette-wrapping machines and the feed belt of the carton-closing 55 and sealing machine and operate continuously

without attention of any sort to pack the packages of cigarettes in the cartons.

A further object of the invention is to provide a machine of this character which can be operated at high speed so that one carton-filling 5 machine will successfully take care of the output of three or more wrapping machines.

In the accompanying drawings I have illustrated a preferred embodiment of my invention, and in said drawings:

Figures 1a and 1b constitute together a longitudinal section of the entire machine on lines 1a and 1b of Figs. 2 and 3, respectively;

Fig. 2 is a plan view on a somewhat enlarged scale of a portion of the mechanism shown in 15 Fig. 1a;

Fig. 3 is a plan view of part of the mechanism shown in Fig. 1b;

Fig. 4 is a horizontal sectional view of the same portion of the machine on line 4—4 of Fig. 1b; 20

Fig. 5 is a vertical sectional view on line 5—5 of Fig. 3;

Fig. 6 is a transverse sectional view on line 6—6 of Fig. 3;

Fig. 7 is a detail view on an enlarged scale on 25 line 7—7 of Fig. 1a;

Fig. 8 is a detail view on line 8—8 of Fig. 2;

Figs. 9 and 10 are detail views of the automatic switch mechanism for controlling the operation of the machine, on the correspondingly 30 numbered lines of Fig. 1b.

Fig. 11 is a detail sectional view on line 11—11 of Fig. 4;

Fig. 12 is detail view of one of the flights of one of the feed chains for the cartons; 35

Fig. 12a is a similar view of one of the flights of another feed chain for the cartons;

Figs. 13—19, inclusive, are sectional views, partly diagrammatic, showing the successive operations of the machine; and

Fig. 20 is a schematic view showing the electric control mechanism for the machine. 40

The machine comprises primarily two parts, namely, a cigarette package assembling and delivering mechanism illustrated in Fig. 1a, and a 45 carton filling mechanism illustrated in Fig. 1b, the two being connected by a continuously driven feed belt 1 driven directly by a separate driving motor 2 designated as a belt motor, suitably mounted on the frame of the carton-filling portion of the machine.

The package assembling and delivering mechanism is illustrated in Figs. 1a, 2, 7, and 8. This mechanism comprises a bed plate 3 supported on suitable columns 4 arranged to underly the dis- 55

charge ends of the delivery chutes 6 leading from the several package-wrapping machines of which three are illustrated in Fig. 1a. The cigarette packages are indicated at P and are advanced 5 along the chutes toward the bed plate 3 under a yielding pressure from another source, not shown, and are intermittently discharged from the chutes by an escapement mechanism operating in timed relation with the feed belt 1. This mechanism is 10 illustrated in Figs. 7 and 8 and comprises a pair of bell cranks 7 mounted on vertical rock shafts 8 supported in a bracket 9 which is attached to the side of the bed plate 3 and serves also to support the free end of the chute 6. The escapement 15 mechanism is duplicated for each of the delivery chutes and will be described with respect to one of them.

The bell cranks 7 have their ends overlying the bed plate turned inwardly toward each other 20 to engage and hold the line of cigarette packages as advanced along the chute. The bell cranks are yieldingly held in their inner positions by a suitable spring 10 and at their lower ends the shafts of the bell cranks are provided with cam 25 rollers 11 engaging the opposite sides of a cam 12 mounted on a shaft 13 underlying the bed plate and continuously driven in unison with the feed belt 1.

Also driven in unison with the feed belt 1 is a 30 conveyor chain 14 whose upper reach runs in a slot in the bed plate 3, the chain being provided with feed fingers or rollers 15 projecting upwardly from the upper reach of the chain into the feed trough 16 of the bed plate into which the packages are intermittently discharged, as illustrated 35 in Fig. 7, upon each operation of the cam 12 of the escapement mechanism. The escapement mechanism is designed so that but one package from each feed chute will be dropped in the trough 40 16 of the bed plate 1.

To prevent more than one package being discharged spring-retaining fingers 17 are provided along each side wall of the chute 6, the ends of the fingers projecting beyond the side walls of the chute and engaging the sides of the last package 45 but one in the chute. That is, the distance between the ends of the fingers 17 and the inturned ends of the bell cranks 7 is somewhat greater than the thickness of the package, so that the last package in the chute will be clear of the fingers 17 and ready to drop into the trough 6 when the bell cranks are opened, the floor of the chute being cut off back of the ends of the bell cranks a sufficient distance for the package 50 to topple of its own weight into the trough when the bell cranks are opened.

In order that the spring fingers 17 will not 60 scuff or injure the packages which are usually wrapped in glassine wrappers and may consequently be easily damaged, the fingers 17 of their own resilience stand apart sufficiently at their outer ends to clear the side edges of the packages, the fingers being pressed together against the edges of the packages by rearwardly extending arms 18 of the bell cranks 7. Hence when the bell cranks are opened by the cam 12, at which time the advancing packages will have come to 65 rest, the fingers 17 will be pressed against the sides of the now stationary package and hold it against movement until the bell cranks are closed, the closing movement of the bell cranks releasing 70 the pressure of the spring fingers 17, thereby allowing the column of cigarettes to be advanced against the bell crank without undue friction 75 against the fingers 17.

The several feed chutes 6 are so positioned and the cams 12 are so timed with respect to the movement of the chain 14 that the packages will be delivered from the chute 6 which is nearest adjacent the distant end of the feed chain 14 5 just in advance of the flight of the roller 15 reaching the position to engage the package. The next feed chute 6 will be so positioned and its escapement so operated as to deliver the package just in advance of the package delivered by 10 the first mentioned chute, and so on, so that in the normal operation of the machine with all the chutes maintained full of packages so that each one will deliver a package to the feed chain 14 15 upon each cycle of operations, there will be delivered to the feed belt 1 a row of cigarette packages which are carried by the feed belt 1 to the carton-filling portion of the machine in a continuous row of closely adjacent packages, as 20 illustrated in Fig. 1b.

The carton-filling mechanism is illustrated in 25 Figs. 1b, 3-6 inclusive, and Figs. 9, 10, 11, and 12. Except for the feed belt 1 the parts of the carton-filling mechanism are operated from a separate motor designated the machine motor and 30 illustrated at 19 in Fig. 5. The operation of this motor is controlled by the movement of the packages through the machine through an automatic control mechanism illustrated schematically in Fig. 20, which will be later described. For the 35 present it is sufficient to say that the control system is so designed that so long as the packages enter the machine in an unbroken row and the cartons are likewise supplied to the machine at proper intervals, the various parts operate 40 continuously and in properly timed relation to place ten packages of cigarettes in each carton. However, if there is any stoppage in the line of cigarettes advanced in the machine, or in the supply of cartons, or in the operation of the 45 mechanism for placing the cigarettes in the cartons, the machine will stop and remain inoperative until the supply of cigarettes or supply of cartons, whichever may have caused the stoppage, has been restored to normal, at which time the machine will again automatically become 50 operative.

In the following description we will assume that the cigarette packages and the cartons will have been supplied to the machine in proper 55 manner. The cigarette packages, as stated before, enter the machine along the feed belt which, as shown in Fig. 1b, extends across a table or shelf 20 supported above the main frame 21 on brackets 22. In their movement across the 60 shelf 20 the cigarettes are guided between edge guides 24 and pass under a series of switch fingers 25 mounted in a housing 26 above the path of travel. The switch controlled by these fingers is shown in detail in Fig. 9.

The switch proper comprises a mercury tube 65 27 supported at one end of a horizontally pivoted shaft as shown in Figs. 20 and 3, and which has a plurality of arms 28 projecting horizontally therefrom. Each finger 25 is supported on a stub 70 shaft 25' projecting inwardly from the adjacent wall of the housing 26 sufficiently to overlie the edges of the packages as they are advanced by the feed belt 1 by the side guides 24. The forward ends of the fingers rest lightly on the advancing packages and their rearwardly extending ends engage the horizontal arms 28. There are five of these fingers 25 arranged so that they rest on five consecutive closely adjacent packages 75 on the belt. As long as the packages are 75

advanced into the machine in a continuous line all five of the switch fingers will be elevated and the machine motor will be maintained in operation. Should one of the fingers drop its rear end will lift one of the horizontal arms 28, thereby causing the mercury to flow to the opposite end of the tube 27 and break the contact through the switch, thereby stopping the machine.

10 Assuming the cigarette packages to continue in the machine in an unbroken line, the advancing package will ultimately reach a stop bar 29 which extends across the feed belt from a fixed bracket 29' mounted on an adjacent portion of 15 the machine frame.

15 The ends of the side guides 24 terminate to the right of the stop bar 29, as shown in Fig. 3, that is, to the rear in the direction of the movement of the feed belt, a distance slightly greater 20 than the width of five adjacent cigarette packages on the belt, and mounted adjacent this portion of the feed belt is a rocking feed pusher 30. The face of the feed pusher consists of a bar 31 having a longitudinal portion long enough to 25 engage the five cigarette packages on the belt between the bar 29 and the ends of the guides 24 and a rearwardly projecting transvers portion 32 adapted when the pusher is rocked to extend across the feed belt 1 and stop the movement 30 of the packages until the pusher is returned to its position of rest alongside the feed belt.

25 The stop bar 29 projects beyond the edge of the feed belt a distance slightly greater than the length of the cigarette packages—that is, their longest dimension, which is transverse of the feed belt in the position in which they are advanced into the machine—and is then bent to provide a longitudinal portion 33 extending parallel with the feed belt and positioned so as to provide a stop for cigarette packages when they are pushed off the feed belt by pusher 32. The end 30 of the stop bar 29 beyond the longitudinal portion 33 is bent backwardly toward the feed belt in close proximity with the end of the bar 24 so as to prevent displacement of the cigarettes in a longitudinal direction, the construction being such that when the feed pusher is rocked to its extreme position when shifting the cigarette packages off the belt, the pusher and the stop bar 29 enclose the cigarette packages on all four sides and thus insure that the group of packages is accurately and exactly positioned at each operation.

35 As shown in Fig. 6, the guide 29 coincides with three sides of a vertical chute 34 down which the cigarettes in groups of five as shifted from the feed belt 1 are forced by a vertically operating feed plunger 35. The chute 34 is of a height to 40 maintain when filled, five rows of cigarette packages, the packages being supported therein by spring fingers 36 projecting downwardly from the lower edge of the feed chute. The plunger 35 operates on each reciprocation to force a new row 45 of five packages into the top of the chute and simultaneously discharge a row of five packages from the bottom of the chute into the carton which has in the meantime been positioned under the chute by the carton-feeding mechanism which 50 will be later described.

55 The rocking pusher 30 is operated by a cam 37 suitably supported on the main frame of the machine and continuously driven from the machine motor through suitable sprocket chain connections which need not be described in detail.

The cam consists of a disk with diametrically projecting cam parts adapted to engage the cam roller 38 carried by the supporting arm of the pusher 30, the cam projection being so shaped as to effect a quick movement of the pusher across the belt 1 and back at each half revolution of the cam shaft, thereby leaving the belt unobstructed during the greater portion of the time and interrupting the movement of the cigarette packages into the machine for brief intervals of time only.

10 The vertical plunger 35 is attached to a cross head 39 mounted for reciprocation in vertical guides 40 supported on a bracket projecting upwardly from the member 21. The cross head 39 is supported on a spring 41 carried by a guide 15 post 42 supported on the same bracket as the guides 40, and the plunger is depressed at intervals by means of a cam 43 overlying a roller 44 projecting from the rear face of the cross head 39. The cam 43 is driven continuously through a 20 sprocket 45 from the shaft 46 which carries the cam 37 so that the two operate in synchronism, the plunger 35 operating immediately after the pusher 30 to force the row of cigarettes advanced by the pusher down the chute 34.

25 The cartons designated C in the drawings are fed into the machine along a feed chute 50 extending laterally from the machine at the level of the bed plate 21. The cartons are positioned in the chute 50 with their flaps open and projecting upward and downward as illustrated in Figs. 13, et seq. Any suitable means (not shown) may be provided for advancing the cartons along the chute 50. It will be understood that in the normal operation of the machine the cartons are fed 30 along the chute in the direction of the arrow in Fig. 3 at a sufficiently rapid rate for a fresh carton to reach the end of the chute in time to be engaged by the feeding fingers 51 carried by the 35 carton feed chain 52 engaged by sprockets supported in brackets 53 projecting upwardly from the bed plate 21 of the machine and driven continuously from the machine motor.

40 The sprockets of the feed chain 52 are mounted for rotation on horizontal axes so positioned that 45 the lower reach of the feed chain extends alongside the path of travel of the cartons from the feed chute 50. The feed fingers 51 project laterally from the sprocket as shown in detail in Fig. 12. Each finger comprises a fixed part 54 50 fixedly attached to the sprocket chain and a finger 51 pivoted on the part 54 and yieldingly held at right angles to the path of movement of the chain so that should the movement of the 55 cartons be obstructed the fingers will yield.

55 Means are provided to stop the machine in the event the cartons are not fed continuously to the machine. This means comprises a switch 58 supported in a housing attached to the under side of the bed plate 21 adjacent the end of a chute 50 60 and consisting of a mercury tube 55 carried by a lever 56 whose upper end projects through the bed plate 21 and is provided with an arm or stop 57 positioned to be engaged by the successive cartons as they are advanced along the 65 chute 50. A light spring holds the stop 57 projected into the path of the cartons so that as each carton is moved away from engagement with the stop by the action of the feed sprocket 52 the lever will be rocked by the spring, thereby tilting 70 the mercury tube and breaking the circuit. This switch, however, is arranged in parallel with other switches so that should the succeeding carton in the chute 50 be immediately projected against the finger 57, as will be the case if the cartons are 75

supplied continuously, the lever 50 will be oppositely tilted and the circuit closed before the circuit is opened through the parallel connection, as will be described.

5 Under the action of the feed chain 52 the open cartons are advanced to a feed chain 60 whose upper reach runs along the bed plate 21 beneath the chute 34 and thence beyond the frame of the machine to discharge the filled cartons into the delivery chute 61 which may advantageously lead to the carton-closing machine of our companion application above referred to.

There are, in fact, two feed chains 60, one on each side of the path of travel of the carton provided with yielding fingers 62a and cross lugs 62. The yielding fingers 62a (shown in detail in Fig. 12a) engage and move the carton along the bed plate 21 to the filling position beneath chute 34. When the carton reaches this position, its motion is arrested by a stop mechanism to be later described, and because of the yielding nature of fingers 62a, they release the carton when it is arrested and slide along the sides of the carton as shown in Figs. 13 to 18, inclusive.

25 Means are provided for lifting the cartons when they reach a position in alignment with the chute 34. This means comprises a plunger 63 supported for vertical movement by a bracket 64 supported on the lowermost bed plate 65 of the machine. The plunger 63 is elevated by a cam 66 attached to the shaft 46 which carries the cam 37 so as to operate in proper timed relation therewith. The plunger 63 is normally held in its lowermost position by springs 67 and is supported on the cam 66 by means of a cam roller 68 which projects from the rear face of the plunger. The periphery of the cam is circular except at the position of its operating projection and thus serves to maintain the upper face of the plunger flush 35 with the bed plate to receive the cartons as they are advanced by the chains 60.

Also mounted for vertical reciprocation through the bed plate 21 is a positioning finger or arm 69, whose construction is best shown in Fig. 5 as 45 mounted immediately in front of the plunger 63 and is operated in proper sequence by means of a cam 70 carried by the shaft on the outer sprocket 71 of the sprocket chains 60.

A bell crank 72 is supported on the machine 50 frame in position for one arm to engage the cam 70 and the other arm to engage and operate the arm 69. The purpose of the arm 69 is to stop the advancing movement of the carton in a position immediately beneath the chute 34 so that 55 when the carton is elevated by the plunger 63 it will be in proper registry with the chute so that the flaps of the carton will project upwardly around the fingers 36 which support the bottom-most row of packages in the chute and thus insure the proper placing of the cigarettes in the carton. For this purpose the stop arm 69 is reciprocated from a position beneath the face of the plunger 63 when the latter is in its lowermost position to a position above the face of the plunger 63 when the latter is elevated, thereby stopping the forward movement of the carton when the plunger is elevated but allowing it to move forward when the plunger is lowered and the lugs 62 engage the rear end of the carton.

70 The cam 66 for operating the plunger 63 has but one operating projection instead of two, so that pusher 30 and plunger 35 operate twice for each operation of the plunger 63 and thereby force two rows of packages of five each into the 75 carton. The operation of the feed chains 60

and the arrangement of the lugs 62 thereon is such that as the plunger 63 reaches its lowermost position and the stop arm 69 is withdrawn from its position in front of the carton, the lugs will engage the carton and feed it out of the machine 5 into the delivery chute 61.

The operation of the machine will no doubt be sufficiently understood from the foregoing description, but will be briefly summarized. The cigarette packages from the three or more feed 10 chutes 6 are assembled on the conveyor chain 14 so as to provide normally a continuous row of cigarette packages on the feed belt 1, by which they are conveyed along the upper shelf 20 of the 15 carton filling machine. These packages pass in a continuous row under the switch fingers 25, all five of which must be elevated in order for the machine to operate. In the electrically controlled mechanism illustrated in Fig. 20, as there 20 shown it will be observed that the belt motor 2 is mounted directly across the main leads of the circuit so as to be continuously operated independently of the rest of the mechanism. This belt motor operates the feed belt 1, the feed chain 14 and the other parts of the package-feeding 25 and assembling mechanism, but does not operate any of the parts of the carton-filling machine, all of which are operated from the machine motor.

The circuit for the machine motor is controlled primarily by manual push buttons, so labeled, in 30 Fig. 20, whereby the operator may stop the carton-filling machine while allowing the belt motor to continue to operate. When the circuit is closed through the push button control, it passes first to a junction point 74 from which one 35 branch leads to a mechanical switch 75 supported on the shaft 46, while the other branch leads to the switch 58 controlled by the incoming cartons. The two branches of the circuit are united at a second junction point 76 from which 40 the lead extends to the switch fingers 25 which, as stated above, are arranged so that the dropping of any one of the switch fingers will break the circuit.

From the switch fingers 25 the current is conducted to the other terminal of the circuit. By this arrangement the mechanical switch 75 and the carton control switch 58 are in parallel and each is in series with the switch 27. The mechanical switch 75 is operated from a cam 77 on 50 the shaft 46. The cam has two operating projections positioned, respectively, slightly in advance of the operating projections of the cam 37. The switch 75 is normally closed so that the machine will remain in operation, assuming the line 55 of packages on the shelf 20 is continuous, regardless of the condition of the switch 58.

Just before the cam 37 acts to operate the pusher 30, the cam 77 will operate to break the circuit so that unless at this moment there is a 60 carton in its proper position ready to be advanced into the machine, the machine will be stopped and will not resume operations until the carton is advanced into the machine and the switch 58 is closed. As soon as this takes place, the operation of the machine will begin, irrespective of the switch 75 being open.

The feed belt 1 operates continuously and upon any stoppage of the machine the feed belt slips under the packages which are held against movement by the stop bar 29. The machine will stop as soon as the gap in the cigarette line reaches the rearmost finger 25 and will not start again until this finger is again closed. Thus, one finger 75 will ordinarily serve to maintain the machine 70

in proper operation to insure the full charge of packages for each carton. However, by providing five such switch fingers all of which must be closed for the machine to operate, an unbroken line of packages is insured from that point on.

5 The machine is designed to operate at high speed as compared with machines of this type generally; for that reason the stop bar 29 is shaped to surround the charge of cigarettes at 10 the chute 34 and thus check any momentum the packages may have due to the rapid movement of the pusher 30.

15 The stop finger 69 is projected into the path of the oncoming carton which under the action of yielding fingers 62a of feed chain 60 is carried against the stop 69 after the plunger 63 elevates it above the top of the feed lugs, thus insuring its accurate positioning with regard to the feed chute 35.

20 The carton is held against lateral displacement during the loading operation by the side guides 18 carried by the plunger 63 into which the carton is directed by the fixed guides 19. The side flaps are held open while the packages are 25 placed therein by the flap guide 13 which surrounds the lower end of the chute 34. The cartons are placed in the feed chute 50 with their flaps folded outwardly and the end flaps are long enough not to turn inwardly under the 30 natural resilience of the paper. The shorter side flaps, however, sometimes show a tendency to project inwardly beyond the vertical. The guide 35 13, however, has the cartons carried under it by the feed chains 60 and projects between the side flaps and spreads them apart so as not to interfere with the packages of cigarettes as they are delivered into the carton.

30 The machine has been found substantially fool-proof in operation even when operated at a high rate of speed.

40 It will of course be understood that while the construction and operation of the preferred embodiment of the machine have been described in

detail, the invention is not limited to such details except insofar as recited in the appended claims.

I claim:

1. In a machine of the class described, the combination of means for assembling a charge of articles, means for placing said charge of articles into a carton, means for advancing the cartons into said machine into position to receive the articles, said means comprising a continuously operated conveyor for feeding the cartons toward the machine, a stop mechanism in the path of said cartons, means for feeding the cartons away from said conveyor, and means controlled by said stop for actuating said last-named means whereby said means will be rendered operative only 15 when a carton is advanced against said stop.

2. In a carton-filling machine, a conveyor for advancing a continuous succession of articles into said machine, means controlled by the articles so advanced for periodically shifting a predetermined number of articles off said conveyor, article assembling means for superimposing the successive groups of articles so fed in successive layers one resting upon another and for simultaneously discharging a layer of articles therefrom, and means for supporting a carton with its mouth adjacent the lower portion of said article-assembling means to receive the discharged layer of articles.

3. In a machine of the class described the combination of means for assembling a charge of articles, means for placing said charge of articles into a carton, a continuously operated conveyor for feeding cartons toward the machine, a stop mechanism in the path of said cartons, a second conveyor adapted to receive the cartons from said first conveyor and advance them into position to receive the articles, and means controlled by said stop mechanism for actuating said second conveyor whereby said conveyor will be rendered operative only when a carton is advanced against said stop.

CORNELIUS I. BRAREN.
